(57) **CLAIM**

The ornamental design for a grill handle, as shown and described.

DESCRIPTION

FIG. 1 is a perspective view of a grill handle showing our new design;

FIG. 2 is a front view of the handle, the rear view being a mirror image;

FIG. 3 is a perspective view thereof;

FIG. 4 is top side view thereof;

FIG. 5 is a right side view thereof, the left side being a mirror image; and,

FIG. 6 is a bottom view thereof.

The details shown in broken lines form no part of the claimed design.
